UNITED STATES PATENT OFFICE.

ELMER J. TIMMONS, OF CINCINNATI, OHIO.

SWINGING SHELF FOR DESKS, &c.

SPECIFICATION forming part of Letters Patent No. 694,445, dated March 4, 1902.

Application filed June 3, 1901. Serial No. 63,019. (No model.)

To all whom it may concern:

Be it known that I, ELMER J. TIMMONS, a citizen of the United States, residing at Cincinnati, in the county of Hamilton and State of Ohio, have invented a new and useful Swinging Shelf for Desks, &c., of which the following is a specification.

The invention relates to improvements in swinging shelves for desks, tables, and the like.

The object of the present invention is to improve the construction of swinging shelves for desks, tables, and the like and to provide a simple, strong, and inexpensive one designed to be mounted at one corner of a table or desk for holding a type-writer or for any other purpose and adapted to be readily swung to arrange it at the front of the desk or to position it at the end of the same and capable when not in use of being compactly folded against the end of the desk.

A further object of the invention is to provide a swinging shelf of this character adapted to dispense with the sliding shelves or supports of roll-top and other desks and capable of being readily mounted on the same and of convenient removal therefrom when desired.

The invention consists in the construction and novel combination and arrangement of parts hereinafter fully described, illustrated in the accompanying drawings, and pointed out in the claims hereto appended.

In the drawings, Figure 1 is a perspective view of a swinging shelf constructed in accordance with this invention and shown applied to a desk. Fig. 2 is a perspective view of the shelf detached. Fig. 3 is a vertical sectional view illustrating the manner of folding the shelf against the desk.

Like numerals of reference designate corresponding parts in all the figures of the drawings.

1 designates a rectangular shelf designed to be arranged at the corner of a table or desk, as illustrated in Fig. 1 of the accompanying drawing, and hinged at one of its edges to a supporting-bracket 2, which is provided with vertical pintles 3 and 4, removably arranged within eyes 5 and 6 of angle-leaves 7 and 8. The angle-leaves 7 and 8 are suitably secured to the desk, at one corner thereof, and the

shelf is adapted to swing horizontally on the vertical pintles of the bracket to arrange it in front of the desk or at the end of the desk, 55 and it is also adapted to swing on the hinges which connect it to the bracket to fold it against the end of the desk, as illustrated in Fig. 3 of the drawings. The supporting-bracket is provided at its top with horizontally-projecting lugs or ears 9, located at the inner face of the supporting-bracket and extending inward beneath the shelf 1 when the latter is in a horizontal position, and the said shelf is provided with bifurcated plates or 65 leaves 10, perforated for the reception of pintles 11, which pass through the perforated lugs or ears 9 of the supporting-bracket. The pintles are located near the ends of the lugs and are offset sufficiently from the supporting-bracket to provide a space between the same and the shelf when the latter is swung downward to accommodate a folding brace 12. The folding brace 12 is provided at its inner vertical rear edge with pintles 13 and 14, 75 arranged in perforated ears 15 and 16, projecting laterally from the inner side of the supporting-bracket, as clearly illustrated in Fig. 2 of the accompanying drawing. By this construction the folding brace is adapted to 80 swing to and from the supporting-bracket 2 to provide a support for holding the shelf in a horizontal position and to permit the same to swing downward for folding. The outward movement of the brace 12 is limited by a keeper 85 17, secured to the lower face of the shelf and having an angularly-bent downwardly-offset portion which is spaced from the lower face of the shelf to form a recess for the reception of a projecting portion or lug 18 of the folding 90 brace. The folding brace is also provided at its top with inner and outer recesses 19, adapted when the parts are folded to receive the plates or leaves 10 of the shelf.

The supporting-bracket and the folding 95 brace, which are approximately triangular, as clearly illustrated in Fig. 2, may be constructed of any ornamental design, and the shelf, which may be of any desired size, is adapted to be swung horizontally on the vertical pintles of the supporting-bracket to arrange it either at the front or end of the desk, and it is also capable of swinging vertically on the pintles 11 to arrange it in a horizontal

position for use and to fold it when not in use. The upper angle-leaf 7 is preferably provided with a cam edge 20, arranged to form a stop for holding the shelf in either position, and it 5 will enable the shelf to readily ride over it.

It will be seen that the shelf is exceedingly simple and inexpensive in construction, that it possesses great strength and durability, and that it is adapted to be readily applied to the 10 corner of a desk or table. Also it will be seen that the shelf may be readily swung to the front or end of the desk or table and that when not in use it may be compactly folded against the same and that when in a horizontal 15 position it is firmly held in either position and may be used for supporting type-writers, telephones, and other instruments and for any use to which an ordinary shelf may be put.

What I claim is—

20 1. A device of the class described comprising a supporting - bracket designed to be mounted at the corner of a table or desk and provided at its top with projecting lugs or ears, a shelf having leaves or plates hinged to the 25 lugs or ears of the bracket, the folding brace mounted on the bracket and arranged to swing horizontally and provided with recesses or openings to receive the leaves or plates and

the lugs or ears to permit it to fold to a position between the bracket and the shelf, and 30 the keeper 17 arranged beneath the shelf and mounted thereon, said keeper being open at its inner end and arranged in the path of the brace and adapted to be automatically engaged by the same when the brace is swung 35 outward, substantially as described.

2. A device of the class described comprising a supporting - bracket designed to be mounted at the corner of a table or desk and provided at its top with projecting lugs or ears, 40 a shelf provided with leaves or plates hinged to the lugs or ears of the bracket, and the folding brace mounted on the bracket and arranged to swing horizontally and provided with recesses or openings to receive the leaves 45 or plates and the lugs or ears, whereby it is adapted to fold to a position between the bracket and the shelf, substantially as described.

In testimony that I claim the foregoing as 50 my own I have hereto affixed my signature in the presence of two witnesses.

ELMER J. TIMMONS.
